UNITED STATES PATENT OFFICE.

CHRISTOPHER B. DETWILER, OF McARTHUR TOWNSHIP, LOGAN COUNTY,
OHIO.

FENCE-POST.

SPECIFICATION forming part of Letters Patent No. 761,455, dated May 31, 1904.

Application filed January 20, 1904. Serial No. 189,929. (No model.)

To all whom it may concern:

Be it known that I, CHRISTOPHER B. DETWILER, a citizen of the United States, residing in McArthur township, in the county of 5 Logan and State of Ohio, have invented a new and useful Improvement in Fence-Posts, of which the following is a specification.

In the drawings, Figure 1 represents a sectional view of my device, showing two of the 10 cables embedded in the post and the bolts for holding the fastening device. Fig. 2 is a horizontal sectional view of my post through line $\alpha\alpha$. Fig. 3 is a side view of my adjustable fastening device; Fig. 4, perspective 15 view of my post with the fastening device in position and bolted in place to hold fence-wires.

In the accompanying drawing, A represents 20 my fence-post, made of concrete, cement, or artificial stone, which may be made of any desired length or thickness or of any desired shape. The post A is provided with four wire cables E, embedded in the concrete and extending the length of the post. These 25 cables are composed of two or more wires twisted together and act as a support, although iron rods or bars may be used. The twist gives the cables an irregular surface that provides the support by holding the plastic material together and prevents the destruction 30 of the post even when cracked or broken.

My fastening device for the purpose of 35 clutching and holding the fence-wires in position consists, preferably, of an iron bar B, that fits in groove D in the post and after the wires are in place is firmly held in the groove

by means of bolts C. The inner edge of the bar is notched, as shown, to catch and hold the wires at any point desired on the posts, and the bar B can be moved endwise in the 40 groove to adjust the wires to any height on the post. The notches in bar B being close together, it is adaptable for fences of varying distances between the strands or to hold woven-wire fence of any mesh.

In operation my posts are set in line for a 45 fence. The wires are stretched alongside the posts on the grooved side. The notched bar B is then placed against the wires, which are placed in the proper notches to space them 50 the required distance apart. The bar is then pushed into the groove D and bolted tight by means of bolt C.

By means of my device a new fence is 55 readily built, an old one repaired, or a broken wire replaced, and the distance between strands adjusted perfectly. The notches being close together, like saw-teeth, the wires of a fence can be adjusted accurately and regularly.

What I desire to claim is—

1. A post having a vertical groove therein, an adjustable clamping-bar, and devices for fastening the bar to the post, as and for the purpose set forth.

2. In a concrete, grooved, fence-post, the 65 notched bar, and means for securing the bar to the post, as and for the purpose set forth.

CHRISTOPHER B. DETWILER.
